UNITED STATES PATENT OFFICE.

CHARLES J. DAVOL, OF PROVIDENCE, RHODE ISLAND, ASSIGNOR TO THE
DAVOL RUBBER COMPANY, OF SAME PLACE.

DESIGN FOR A SYRINGE.

SPECIFICATION forming part of Design No. 31,279, dated July 25, 1899.

Application filed June 22, 1899. Serial No. 721,486. Term of patent 14 years.

To all whom it may concern:

Be it known that I, CHARLES J. DAVOL, of Providence, in the county of Providence and State of Rhode Island, have invented and produced a new and original Design for a Syringe, of which the following is a specification, reference being had to the accompanying drawings, forming part thereof.

Figure 1 is a side view of a syringe, showing my design. Fig. 2 is a sectional view of the same on the line A A of Fig. 1.

The leading feature of my design consists in the spherical outline of the bulb, having an annular base and a long tapering neck, surrounded by an outwardly and upwardly extending flange, presenting to the eye the appearance of a bulbous flask with an upwardly-projecting stopper.

In the drawings, *a* indicates the spherical

body; *b*, the annular base; *c*, the tapering tubular neck; *d*, the upwardly and outwardly curved annular flange, and *e* the nozzle end of the tubular neck, tapering gradually to the rounded end. The slightly-raised bead *f* extends around the equatorial line of the spherical body *a*.

Having thus described my invention, what I claim as new, and desire to secure by Letters Patent, is—

The design for a syringe substantially as herein shown and described.

In witness whereof I have hereunto set my hand.

CHARLES J. DAVOL.
